CLAIM

The ornamental design for a speed detector, as shown and described.

DESCRIPTION

FIG. 1 is a perspective view of a speed detector showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The broken lines shown on the drawings are included for the purpose of illustrating unclaimed features of the speed detector and form no part of the claimed design.
